UNITED STATES PATENT OFFICE.

FREDERICK SHICKLE, OF ST. LOUIS, MISSOURI.

FIRE-ESCAPE.

SPECIFICATION forming part of Letters Patent No. 312,910, dated February 24, 1885.

Application filed June 9, 1884. (No model.)

To all whom it may concern:

Be it known that I, FREDERICK SHICKLE, of St. Louis, Missouri, have made a new and useful Improvement in Fire-Escapes, of which 5 the following is a full, clear, and exact description, reference being had to the annexed drawings, making part of this specification, in which—

Figure 1 is a front elevation of the improved 10 fire-escape in position, the building-front being shown in broken lines; Fig. 2, a front elevation, upon an enlarged scale, of the escape; Fig. 3, a side elevation of the escape, the building-front being shown in vertical section; and Fig. 4, a horizontal section on the 15 line 4 4 of Fig. 3.

The same letters of reference denote the same parts.

The present invention is an improvement 20 in that class of fire-escapes having a ladder adapted to be moved along the building front and sides.

The improvement relates to the construction 25 of the ladder and to the means by which it is attached and adjusted upon the building.

A represents the ladder.

B represents a rail attached by means of brackets, such as b, to the building C at or toward its top.

30 The ladder consists of a tube, a, and the rounds a', the tube being arranged centrally in the ladder, and serving both to support the rounds and as a means by which a stream of water can be conducted upward onto the building. The ladder, by means of the hanger D and pulley E, is suspended upon the rail B, and adapted to be moved thereupon.

The mechanism for moving the ladder along the building-front is as follows: A rope or 40 chain, F, passes around the sheaves a² a² and the pulley G. This last-named pulley is at-

tached to the shaft g, which in turn is held in the hanger D, and is provided with the pinion H. This pinion engages with the gear I upon the shaft e of the pulley E. By drawing the rope or chain F the pulley E can be rotated, and according to the direction in which it is rotated is the ladder moved along the building-front. To enable the ladder to be turned around, it is at a³ swiveled to the 45 upper portion, a⁴. Above the point at which the ladder is swiveled an extension, a⁵, leads outward and upward, and then inward, if desired, to enable the stream of water to be conducted directly onto the roof of the building, 50 and substantially as indicated in Fig. 3. The lower part, a⁶, of the ladder can thus be turned around without affecting the position of the extension a⁵. The entire device can 55 also be swung or inclined or tilted into various positions with relation to the building-front without detaching it from the rail B.

I claim—

1. The combination of a ladder suspended from a pulley mounted on a rail, and provided 60 with gears, and an endless rope or cable, with a central tube having rounds projecting from both sides of the said tube, as described.

2. The combination of a swiveled tube having rounds a' secured to it, with rolling sus- 65 pension mechanism, and an endless rope or cable for actuating the same, substantially as described.

3. The combination of the rail B, the hanger D, and the ladder A, swiveled at a³, as and 70 for the purpose described.

Witness my hand.

FREDERICK SHICKLE.
